Inventor
John Oleszko

UNITED STATES PATENT OFFICE

JOHN OLESZKO, OF DETROIT, MICHIGAN

FLOOR DRAIN AND AUTOMATIC FLOOD PROTECTOR

Application filed May 13, 1929. Serial No. 362,732.

This invention relates to a floor drain and automatic flood protector, and it is the principal object of my invention to provide a device of this character in the form of a check-valve, the floating body of which will close effectively the drainage opening of a sewer trap against the detrimental influence of the sewer water backing into a cellar.

Another object of my invention is the provision of a device of this type equipped with means for seating a ball allowing its floating to close the mouth of the sewer opening as soon as water backing from the sewer tries to enter the cellar.

15 A further object of my invention is the provision of a device of this character equipped with means to guide the ball back onto its seat after each operation.

A still further object of my invention is the provision of a check valve protecting cellars against being flooded by backing sewer water equipped with means for protecting the sewer opening against the entrance of impurities, refuse or the like.

25 These and other objects of my invention will become more fully known as the description thereof proceeds, and will then be specifically defined in the appended claim.

In the accompanying drawings forming a material part of this disclosure:

Fig. 1 is a sectional front elevation of a device constructed according to my invention, the section being taken on line 1—1 of Figure 2.

35 Fig. 2 is a top plan view of the device after the removal of the cover.

Fig. 3 is a longitudinal section through the device on line 3—3 of Figure 1.

Fig. 4 is a detail plan view of the cover plate.

As illustrated, my floor drain and automatic flood protector comprises a hollow body 10 adapted to be placed upon or connected with a sewer drainage pipe or the like, and 45 having substantially the form of a frustated cone having a laterally extending ball socket 11 formed therewith normally holding a hollow ball 12 of rubber or similar suitable material.

50 Integrally made with the upper end of the

body 10 is a seat 13 presenting a bowl shaped member or element 14 having a seat or flange 15 formed with its inner edge for seating a cover plate 16 perforated by a plurality of circularly arranged openings 17 surrounding its center while a plurality of radially extending elongated slots 18 having narrow pointed inner ends and wider rounded outer ends is grouped about the inner circle of openings 17.

The seat 13 has formed therewith an inner groove in which rest the outer ends of cross-wise arranged bars 19 forming a spider 20.

Inclined bars 21 are arranged within body 10 crossing the same from a higher point 22 to a lower point 23 at the union between ball socket 11 and body 10.

The device operates as follows:

When arranged in a cellar or the like, with the top cover 16 flush with the cellar floor and the body 10 in connection with a sewer drainage pipe, a backing of the sewer water will cause the accumulation of water within body 10, floating float ball 12 which will leave its seat 11 and acting as a valve body 70 be pressed against seat 13 closing the opening tightly and preventing water from entering the cellar.

The spider 20 will prevent the ball from rising too high, while the top plate 16 will 80 prevent refuse from entering the body 10 and bars 21 will act as guiding means for the ball to return the same onto its seat, after the receding sewer water has ceased to press against the same from below.

It will be understood that I have disclosed the preferred form of my device only as one example of the many possibilities to practically construct the same, and that I may make changes within the scope of the appended 90 claim without departing from my invention.

Having thus described my invention, what I claim as new and desire to secure by Letters Patent is:

In a cellar drainage device and sewer closure, a body having substantially the shape of a cone frustum, and adapted to be connected with a sewer drainage pipe, a laterally extending ball socket formed with said body, a ball float in said socket, a seat inte- 95

grally formed with the upper end of said body having an inner groove a bowl, the bottom of which is formed by said seat, an upper flange on said bowl having an inner shoulder, a plate resting on said shoulder and having a plurality of round openings arranged in a circle, and a plurality of radially extending elongated slots having narrow pointed inner ends and wider rounded outer ends, and grouped about said circle of holes, for allowing the draining of the cellar and retaining refuse, a spider formed by cross-wise arranged bars resting with their outer ends in the groove of said seat, for limiting the upward movement of the ball when floated by the sewer water rising in socket and body, and a plurality of inclined bars in said body below said socket for guiding the ball float back into said socket upon recession of the sewer water.

Signed at Detroit, in the county of Wayne and State of Michigan, this 6th day of May, A. D. 1929.

JOHN OLESZKO.
